THERMIONIC OSCILLATION GENERATOR

Bertram John Witt, Eastcote, Middlesex, and Charles Samuel Franklin, Strand, London, England, assignors to Radio Corporation of America, a corporation of Delaware

Application December 18, 1931, Serial No. 581,794
In Great Britain December 20, 1930

1 Claim. (Cl. 250—36)

This invention relates to thermionic oscillation generators and more particularly to thermionic oscillation generators for generating short waves.

5 The invention has for its object to provide an improved thermionic oscillation generator, suitable for generating short waves, in which the frequency generated shall only vary slowly, if at all, with change in filament current in the 10 tube or tubes employed and in which variation in frequency with variation in anode potential applied to the said tube or tubes shall also be very small.

15 According to this invention a thermionic oscillation generator arrangement suitable for use for generating short waves comprises, in combination, a master frequency determining circuit, an amplifier tube having its input circuit coupled to said master circuit, a second amplifier tube having its input circuit coupled to the output circuit of said first mentioned tube and its output circuit coupled back to said master circuit, and a coupling tube having its input circuit coupled to the output circuit of said first 20 mentioned tube, output oscillations being derived from the output circuit of said coupling tube.

25 In one way of carrying out the invention an oscillation generator comprises a master frequency determining circuit which is associated with the input circuit of a first amplifier tube, the grid of said tube being capacity coupled to said master circuit, an anode resistance in the anode circuit of said tube, a further tube having its input circuit capacity coupled to the anode of said first amplifier tube, said further tube having a tuned circuit in its anode circuit and a second amplifying tube having its input circuit capacity coupled to the anode of the first amplifier tube and 30 its anode capacity coupled back to the master circuit, an anode resistance being provided in the anode circuit of said last tube.

35 The invention is illustrated in the accompanying drawing in which Figure 1 shows an arrangement embodying a master frequency determining circuit which may conveniently consist of a unit as described in United States Patent No. 2,028,596, granted January 21, 1936, to C. S. Franklin et al., and Figures 2 and 3 show graphically the 40 characteristics of the amplifying tubes V₁ and V₂ employed in the circuit of Figure 1. The frequency determining arrangement as disclosed and illustrated in said patent and illustrated in Figure 1 of this application includes a coil L and a condenser C, each having one terminal con-

nected to screen E and the other terminal connected with small condensers X and Y as shown, the whole arrangement being enclosed within an earthed screening case E. The variable capacity C and the inductance L form the principal elements of the frequency determining circuit which is enclosed in the shield E. As pointed out more in detail in said patent, the elements X, Y, C, and L are enclosed in said shield E, among other things, to maintain the same at 10 an even temperature free of moisture, etc., so that the frequency determined thereby will be constant or nearly so. Furthermore, as pointed out in detail in said patent, the elements, and in particular the capacities of the frequency determining circuit X, Y, C, are so arranged and mounted in said closure member on supports having different coefficients of expansion than temperature changes which might result in change in one capacity or movement of one plate 20 of a capacity are counteracted by compensating movements in another capacity or an element of a capacity so that the frequency determined by the circuit is constant irrespective of temperature changes. The high potential 25 end of the master frequency determining circuit L, C is connected as shown through a coupling condenser Y to the grid G₁ of a first amplifying tube V₁, the said grid being connected to the earthed cathode F₁ of said tube 30 through a resistance G_{R1}. The anode of tube V₁ is connected to the positive terminal of a source of anode potential AB through an anode resistance A_{R1}, and is also connected through a coupling condenser O to the control grid G_S of 35 a further tube SV. SV is a screen grid amplifier tube whose screening grid is suitably positively biased by a source of potential not shown which may be connected thereto. The plate circuit of the tube SV contains a tuned circuit L₁C₁ which 40 is adapted to be coupled through condensers m n to the first amplifier stage of a radio or similar transmitter (not shown) or to frequency changing circuits as may be required. The circuit L₁C₁ may be tuned to the same frequency as 45 the master frequency determining circuit or to a harmonic thereof. The anode of tube V₁ is also connected through a condenser P and an oscillation damping resistance SR (sometimes termed as "anti-squegger resistance") to the 50 grid of a second amplifying tube V₂ whose anode A₂ is connected through an anode resistance A_{R2} to the source of anode potential and whose grid G₂ is connected through a resistance G_{R2} to the cathode F₂ of said tube, said cathode being 55

earthed. The anode A_2 is connected through a coupling condenser X to the unearthed end of the frequency determining circuit. The screen E serves as the earth point and common cathode point and the negative terminal of the source AB is connected thereto. In operation the tubes V_1 and V_2 serve to maintain the master frequency determining circuit in oscillation, the tube SV serving as an amplifier and coupling tube between 5 said circuit and the amplifier or other device which is coupled through condensers m n .

The following components and circuit values have been found in practice to give satisfactory results as regards relative constancy of frequency 10 with varying filament current and (within limits) 15 varying anode potentials:—

The amplifying tube V_1 is known as the L610. This is a tube of about 7500 ohms impedance having a mutual conductance of 2.0 Ma/volt and provided with a filament taking 0.1 amperes at 6 20 volts. At 100 volts anode potential and with no grid voltage the amplification factor is 15. The characteristics of an L610 tube are shown graphically in Figure 2 of the drawing. With this tube 25 in circuit the value of the grid resistance GR_1 was 75,000 ohms and that of the anode resistance AR_1 , 4,000 ohms.

The second amplifying tube V_2 is known as the P610. This is a tube of about 3500 ohms impedance 30 having a mutual conductance of 2.28 Ma/volt and has a filament taking 0.1 amperes at 6 volts. The amplification factor when the anode voltage is 100 and grid voltage zero is 8. The characteristics of a P610 tube are shown 35 graphically in Figure 3. With this tube the value of the grid resistance GR_2 was 30,000 ohms and the anode resistance AR_2 , 4,000 ohms.

Having now particularly described and ascertained the nature of our said invention and in 40 what manner the same is to be performed, we declare that what we claim is:—

A constant frequency oscillation generator circuit comprising, in combination, a master frequency determining circuit including inductance and capacity enclosed in a metallic screen, an amplifier tube having an anode, cathode, and control electrode, said cathode being directly connected to and said control electrode resistively connected to said metallic screen, said control electrode being coupled to one terminal of said master frequency determining circuit, a second 10 amplifier tube having an anode, cathode, and control electrode, said last cathode being directly connected to and said last control electrode resistively connected to said metallic screen, a connection including a resistance and a condenser in 15 series between the control electrode of said second tube and the anode of said first tube, and a connection between the anode of said second tube and another terminal of said master circuit, a tank circuit comprising an inductance and condenser 20 in parallel tuned to a frequency bearing a predetermined relation to the frequency of said master circuit and individual connections including resistances from a point intermediate the ends of said last inductance to the anodes of both said 25 tubes, a source of potential having one terminal connected to said last point and its other terminal connected to said metallic screen, output leads from said tank circuit from points symmetrically located with respect to said first point on said 30 inductance, a screen grid tube also having an anode, cathode and control electrode, the cathode of said last tube being directly connected to and the control electrode thereof resistively connected to said metallic screen, said control electrode of 35 the screen grid tube being coupled through a condenser to the anode of said first tube, and the anode of said screen grid tube being coupled to said tank circuit.

BERTRAM JOHN WITT.
CHARLES SAMUEL FRANKLIN.
